UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

LOCOMOTIVE STOKER

Application filed March 6, 1926. Serial No. 92,733.

The invention relates to stokers of the type in which fuel is transferred from the tender and delivered to the fire-box above the grate surface, over which it is scattered by suitable means.

The objects of the invention are to simplify and lighten stokers of this character, while securing a high degree of efficiency; to protect the delivery conduit from the destructive heat within the fire-box; to provide for the convenient removal and replacement of the delivery end of the conduit without drawing the fire; and to secure other advantages as will appear in connection with the description of the device.

A desirable embodiment of the invention is hereinafter described, and is illustrated in the accompanying drawing, in which

The drawing is a detail longitudinal vertical section through the locomotive and tender and centrally through the stoking device.

In present railroad practice many locomotives are of such size that their weight reaches closely to the limit permissible in view of the strength of some portions of the track support, such as bridges, and it becomes important to reduce to the minimum the weight of accessory devices, such as stokers, and to distribute this weight.

In the maintenance of stoking devices a serious item of expense is due to the destruction, by the intense heat developed, of the portions of the stoking device which are located in, or project into, the fire-box. It is important not only that the cost of replacement parts be reduced to the minimum, but that where possible, without detracting from the efficiency of the stoker, the latter be so organized and associated with the fire-box that repairs and replacements may be made without necessitating the drawing of the fire and the cooling off of the fire-box to the end that the locomotive may continue in service without material delay for such repairs.

These and other advantages are secured in the stoker herein disclosed.

Portions of a locomotive are represented at 10, its fire-box being indicated at 11, its back-head at 12, and its grate at 13. At 14 there

is shown the floor or deck of the cab. The framing of the locomotive tender is shown at 15, and the floor of its fuel bin at 16.

A fuel-conveying trough 17 is rigidly mounted on the frame of the tender, extending longitudinally thereof and immediately below the floor 16, which is suitably apertured to permit the discharge of fuel into the trough. This trough terminates at its forward end adjacent the forward end of the tender, and within it is located suitable means for advancing the fuel, here shown as a helical screw 18, properly journaled at each end. A motor 19 is here conveniently represented as of the multi-cylinder reciprocating type, its shaft being suitably geared to a driving shaft, not shown, extending backwardly under the floor of the tender as is well known in the art and connected by suitable gearing, conventionally shown at 21, to the shaft of the screw 18. Adjacent the forward end of the trough a crushing jaw or abutment 22 arches over the screw 18, and cooperates with the latter to reduce the fuel to suitable size for use in the fire-box.

Attached to the forward end of the trough 17, by means of a universal joint 23 of the ball and socket type, is a fuel conduit comprising straight sections 45 and 46. This conduit is inclined upwardly and its forward section 46 extends loosely into an opening or aperture 47 in the back-head of the boiler below the usual hand-firing door opening 26 and immediately above the firebox grate 13.

Within this conduit there is located suitable fuel advancing means, here shown as a screw conveyor 48, the shaft of which is connected by a universal joint, as shown at 29, with the forward end of the shaft of the screw 18. The forward end of the screw terminates short of the front end of the feed conduit section 46 in order that it may not be exposed to the destructive heat of the fire. This is quite practicable for the reason that there is no bend or elbow thru or past which the fuel must be forced. The shortening of the screw need not be of any great extent, as it will be protected from the heat by the constantly advancing fuel which, in a device of this kind, will substantially fill the conduit at all times.

Preferably, the forward end of the conduit section 46 does not project beyond, or substantially beyond, the back sheets of the firebox and its rearward end portion incloses the forward end of the conduit section 45, and may extend a considerable distance along it to form a sleeve. The two sections are rigidly secured together by means of suitable bolts, and in event of damage to the forward end of the section 46 by the heat, the bolts may be loosened, the section shoved forward to properly position its delivery end with reference to the firebox, and the bolts again tightened up. When this forward section has been burned away to such an extent that it cannot be readjusted, it may be removed and a new section inserted. This adjustment or renewal can be made without disturbing the fire.

A short distance inwardly from the back-head there is mounted on the grate, and here shown as being applied to the second grate bar, a deflector 49 in the form of an inverted V. The advancing fuel delivered by the feed conduit directly onto the grate 13 is thereby deflected upwardly and caused to build up in a pile, as indicated at 50, the top of the pile coming into the zone of action of horizontally directed steam jets discharging from opening 44 in the nozzle 51, which is disposed above the normal level of the firebed and may be of any suitable construction. The deflector 49 may be provided with apertures through which air may enter for the purpose of keeping it comparatively cool.

The universal joints 23, 29, provide for the flexure of the transfer conduit, which includes the trough 19 and the conduit sections 45, 46, incident to the relative lateral and vertical movements of the locomotive and tender. The loose connection of the conduit section 46 with the backhead of the boiler not only relieves the transfer mechanism from strains incident to such relative movements, but also from strain incident to the relative longitudinal movement of the locomotive and tender due to the compression and expansion of the draft gear connecting the two vehicles, as the conduit section 46 is free to slide within the backhead opening or aperture 47.

Not only is the entire structure comparatively light but by locating the engine 19 on the tender and driving all of the movable parts from it through a single connection, the major part of the weight of the entire device is carried by the tender, and the stoker may be applied to heavy locomotives without involving any problem of excessive weight. The proper distribution of the fuel is easily insured by suitably arranging, directing and proportioning the steam jets of the nozzle 51 to which steam is supplied thru the line 41.

An important feature and an outstanding advantage of the disclosed embodiment of the invention is the placement of the entire trans-

fer conduit beneath the locomotive and tender decks or floors.

Various changes may be made within the scope of the appended claims.

I claim as my invention—

1. In combination, a locomotive having a cab and a deck therefor and a firebox with a grate, said firebox being provided with a backwall having a hand firing opening therein above said grate and having another opening therein between said grate and said hand firing opening, a tender provided with a floor, and a fuel conduit comprising sections universally jointed together, the rearward section being below the tender floor and the forward section projecting loosely through the opening in the back-head of the locomotive fire-box between the hand firing opening and the grate and wholly beneath the deck of said locomotive. 70

2. In combination, a locomotive having a fire-box with a grate, the fire-box having a backwall apertured above said grate, a fuel transfer conduit projecting loosely through the aperture in the back-head of the fire-box whereby relative angular movement of the conduit and back-head may occur, said conduit delivering fuel directly onto said grate, means on the grate separate and apart from said conduit for deflecting the delivered fuel upwardly and means independent of said first-named means for scattering the entering fuel over the area of the grate. 80

3. In combination, a locomotive having a cab deck and a fire box provided with a grate, the back head of the fire box being apertured, said aperture extending to a point below said deck, a fuel conduit projecting through the aperture and delivering directly upon the grate, means for directing fuel upwardly from said grate, and a steam nozzle located above the aperture and discharging approximately horizontally into the fire box across the mass of fuel rising upwardly from the delivery end of said conduit during the operation of said stoker. 100

4. In combination, a locomotive having a fire box provided with a grate, the back head of the fire box being apertured adjacent to the grate, a fuel conduit projecting through the aperture and delivering directly upon the grate, an abutment projecting upwardly from the grate and facing the aperture, and a steam nozzle located above the aperture and discharging approximately horizontally into 110 the fire box.

5. In combination, a locomotive having a firebox provided with a grate and with a backhead having an opening therein immediately above said grate, a tender provided with a floor, a sectional fuel transfer conduit, the two sections being united by a universal joint, the rearward section being fixedly attached to the tender beneath the floor thereof and the forward section projecting loosely 120

and slidably into said opening in the back head of the fire box, immediately above the grate thereof, for delivering fuel directly on to said grate, and means for advancing fuel through the conduit.

5 6. In combination, a locomotive having a firebox with a grate and a backhead having an opening therein above said grate, a tender having a floor, a sectional fuel conduit comprising a rearward section rigidly mounted on said tender beneath the floor and a forward section universally connected to the rearward section and extending forwardly to and arranged to discharge fuel into the 10 firebox through said backhead opening directly onto said grate, said forward section being flexibly mounted with said backhead, means for advancing fuel through said sectional conduit, and a distributing means 15 within said firebox disposed above the normal level of the firebed on said grate for spreading the delivered fuel thereover in aerial paths.

20 In testimony whereof I affix my signature.
